UNITED STATES PATENT OFFICE.

RUDOLPH W. DONMOYER, OF SOUTH BEND, INDIANA.

FIFTH-WHEEL FOR CHILDREN'S CARRIAGES.

SPECIFICATION forming part of Letters Patent No. 235,139, dated December 7, 1880.

Application filed July 9, 1880. (No model.)

To all whom it may concern:

Be it known that I, RUDOLPH W. DONMOYER, a citizen of the United States, residing at South Bend, in the county of St. Joseph and State of Indiana, have invented certain new and useful Improvements in the Fifth-Wheel for Children's Wagons; and I do hereby declare the following to be a full, clear, and exact description of the invention, such as will enable others skilled in the art to which it pertains to make and use the same, reference being had to the accompanying drawings, and to letters or figures of reference marked thereon, which form a part of this specification.

My invention relates to improvements in fifth-wheels for children's wagons; and the object of my improvement is to provide a fifth-wheel to the upper portion of which there is cast or otherwise secured a king-bolt having upon it a projection for locking it to the lower portion, or for preventing the separation of the parts when desired, and a lower portion having at its center an aperture for the passage of the king-bolt, and upon a portion of its periphery a hound to which to attach a tongue. I attain this object by the devices illustrated in the accompanying drawings, in which—

Figure 1 is a front elevation, partly in section, showing one axle of a small wagon, such as are used by children, a bolster placed upon said axle, a fifth-wheel, and a spring, to which the body is attached. Fig. 2 is a vertical cross-section of the fifth-wheel through the center of Fig. 1, showing the spring in position thereon and the projecting hound to which the tongue is attached. Fig. 3 is an inverted plan view of the upper portion of the wheel, showing the bar extending across its center, the king-bolt being shown as having an aperture through it for the passage of a bolt for uniting the parts, it being designed as a modification of the form shown in Fig. 1, which, when used, dispenses with the projections B³ on king-bolt B²; and Fig. 4 is a plan view of the lower portion thereof.

Similar letters refer to similar parts throughout the several views.

In constructing wheels of this character there is provided a section, A, upon which there is formed a circular rim or flange, its up-

per surface being flush with the upper surface of the remaining portion, said flange extending downward far enough to give the ring sufficient strength and to allow it to embrace a 55 projection formed upon the bolster A' or upon the axle.

Across the above-described circular portion of this part of the wheel there is a bar, A², in the center of which there is an aperture, A³, 60 for the reception of a king-bolt, and in the proper position in this aperture there is formed a slot for the passage of a projection on said king-bolt.

From the ring above described there extends a hound or projection, the outer end of which is provided with a recess, A⁴, for the reception of the inner end of the tongue by which the wagon is drawn, and it is also provided with holes A⁵ through its flanges, for 70 the reception of a bolt or pin for attaching said tongue thereto.

The other portion of the wheel consists of a flanged ring, B, having a bar, B', extending across it, upon which there is cast or otherwise formed a king-bolt, B², said bolt having upon it a projection, B³, for entering the slot formed in the portion A for its reception. This bolt is of sufficient length to allow it to pass through A and have its projection turned 80 into such a position as to bear upon the under surface thereof, as shown in Fig. 1, which has the effect to prevent the forward wheels from becoming detached from the body of the wagon while in use, but affording means for disconnecting them when desirable, this being accomplished by turning the parts into such a position as to allow the projection B³ to pass upward through the groove or slot in A. 85

Instead of casting the king-bolt upon the 90 bar B', a rod of wrought-iron may be cast therein, and have a nut placed upon its lower end; or a bolt may be passed through the two bars, and they be thus united and prevented from separating.

Having thus described my invention, what I claim, and desire to secure by Letters Patent, is—

1. A fifth-wheel for children's wagons, consisting of the portion A, having a projection 100 formed or placed thereon, which is bifurcated at its outer end for the reception of the tongue,

and an upper portion having a bar across its center, to which is cast or otherwise secured a king-bolt, substantially as set forth, and for the purpose specified.

5 2. In combination with the forward axle of a child's carriage, or with a bolster, A', placed thereon, the parts A and B, constituting the fifth-wheel, and the spring B⁴, all the parts

being constructed and arranged substantially as set forth.

In testimony whereof I affix my signature in presence of two witnesses.

R. W. DONMOYER.
